UNITED STATES PATENT OFFICE.

CHRISTIAN F. PAUL, JR., OF AUSTIN, TEXAS, ASSIGNOR TO ERNEST NALLE, W. P. ALLEN, AND ED ROSENGREN, TRUSTEES, ALL OF AUSTIN, TEXAS.

CENTRIFUGAL EMULSIFIER.

Application filed June 15, 1921. Serial No. 477,857.

To all whom it may concern:

Be it known that I, CHRISTIAN F. PAUL, Jr., a citizen of the United States of America, residing at Austin, in the county of Travis and State of Texas, have invented certain new and useful Improvements in Centrifugal Emulsifiers, of which the following is a full, clear, and exact description.

This invention relates to devices for mixing or emulsifying two or more liquids, miscible or immiscible, and simultaneously bringing them into intimate association for any purpose, as for example to facilitate quick and complete chemical reaction between a liquid to be treated and a reagent. The production of such an intimate mixture is advantageous in numerous arts, as for instance in the treatment of crude petroleum or other oil with sulfuric acid, and the present embodiment of my invention is designed primarily for that purpose, as described in my copending application Serial No. 477,856; but it is to be understood that the invention is not limited to use in the field indicated.

The invention operates on the centrifugal principle, that is, the liquids to be mixed or emulsified are driven through the mixing or emulsifying devices by centrifugal force, for which purpose the said devices are rotated at a high rate of speed, preferably by means of a steam turbine, direct-connected. The mixing or emulsifying devices are in the form of flat disks arranged co-axially one above the other, and providing between the disks of each pair one or more radial channels of tortuous or "saw-tooth" form, so that in traveling radially outward through such channels the liquids are subject to numerous rapid and sudden changes of direction, thus producing a violent churning effect by which the liquids are brought into almost molecular association with each other. Issuing at high velocity from the emulsifying channels, the spray strikes the walls of the enclosing chamber or casing and is guided downwardly into a collecting trough or receptacle, from which the liquid mixture or emulsion is delivered by a suitable spout or discharge pipe. Preferably the centrifugal mixing or emulsifying devices, forming what may be conveniently termed a mixing and emulsifying head, are driven by direct connection with a single-stage steam turbine.

One form of the invention, embodying the

features outlined above, is illustrated in the accompanying drawings, in which—

Fig. 1 is a side view, partly in vertical section.

Fig. 2 is a detail plan view of one of the mixing or emulsifying disks.

Fig. 3 is a detail side view of a pair of disks, showing the discharge orifices of those of the emulsifying or mixing channels in that pair.

The revolving head, through which the liquids to be mixed are caused to travel by centrifugal force, comprises a hollow spindle or carrier 10, provided with a radial flange 11 on which rests an abutment-plate 12 of circular form. Mounted co-axially on the carrier above the plate 12 is a plurality of pairs (in the present instance two pairs) of mixing or emulsifying disks 13, 14, 15, 16, which are bound firmly together upon the plate 12 by means of the nut 17 threaded on the upper end of the carrier 10. It is advantageous to have the disks fit the carrier snugly, but a driving fit is not necessary or desirable.

One of the mixing disks, as 15, is shown in plan in Fig. 2, in which it will be seen that the disk is provided with four radial grooves or recesses at right angles to each other, into which are fitted four inserts 18, the upper surfaces of which are sharply corrugated or "saw-toothed," as indicated in Fig. 1. All four disks are exactly like that shown in Fig. 2, and the inserts 18 are of such thickness that when the flat surfaces of the disks are in contact (the disks 14 and 16 being inverted over disks 13 and 15 as in Figs. 1 and 3) the corrugated surfaces of the inserts will be slightly spaced apart, thus providing in each pair of disks four tortuous, zig-zag, or "saw-tooth," passages or channels extending radially outward from the carrier 10. As indicated in Figs. 2 and 3, the sides of each insert 18 are parallel to each other and hence the emulsifying passages formed thereby do not flare or widen outwardly. The carrier 10 is provided with a plurality of vertical outlet slots, 19, say two for each vertical tier of passages, or eight slots in all.

When the carrier-and-disk assembly or head is revolved at the desired high speed, liquids delivered into the hollow carrier pass through the outlet or delivery slots 19 into the saw-tooth passages, in a plurality of streams. As the liquids travel outwardly

under the influence of centrifugal force, they are subjected to numerous changes of direction, suddenly and rapidly recurring. The liquids are thus subjected to a violent churning action, which results in the most intimate possible mixing or emulsification. Inasmuch as there is substantially no outward flare or widening of the emulsifying passages, the tendency of the commingled liquids to break up or be atomized into a spray is minimized and there is no decrease in the velocity of outward flow.

The stationary outer casing, which encloses the emulsifying or mixing head, is in the present form composed of three separable sections, seated one on top of the other, as clearly shown in Fig. 1. The lower section 20 is in the form of a circular trough having a vertical outer wall, and an inner wall which is inclined upwardly bringing its edge close to the beveled underside of the abutment plate 12. The center section, 21, is in the form of a circular collar having an inner flange extending upwardly and horizontally over the uppermost mixing disk, 16, as illustrated in Fig. 1. The upper section, 22, is in the form of a flat receptacle or pan, having at its center a discharge tube 23 extending downwardly into the hollow carrier 10. The latter, it will be observed, has at its top an inward overhang, as indicated at 24, to prevent escape of liquid through the open top of the carrier under the influence of centrifugal force, as will be readily understood.

Preferably the rate of delivery of liquids to the receptacle 22, and the speed of the emulsifying or mixing head, are so proportioned or related that the liquid in the carrier will at all times completely cover the outlet slots 19.

The liquid mixture or emulsion discharged from the saw-tooth passages or channels is thrown outwardly at high velocity, but the streams discharged are relatively thin, and hence their momentum is too small to cause much rebound from the surface of the enclosing casing. Accordingly the liquid runs down the walls of the trough 20, and down through openings 25 into the lower circular trough 26 which is removably mounted on the collar 27 extending upwardly from the casing 28. The trough 26 is provided with a discharge spout 26^a from which the collected liquid mixture or emulsion is delivered to another trough, pipe, or launder, not shown, to carry the liquid away for utilization, storage, or such further treatment as may be desirable.

The tubular carrier 10, on which the mixing and emulsifying disks 13, 14, 15, 16 are mounted, has a tapered socket in its lower end to fit tightly (but removably) on the tapered upper end of a vertical shaft 29

which is rotated at a high rate of speed by a steam turbine housed in the casing 28. The turbine rotor 30 is mounted directly on the shaft by means of a hub 31 fitting a taper on the shaft, upon which taper the hub is forced by a nut 32. At its lower end the shaft rests on a ball 33 set in a cup or retainer 34 adapted to slide freely but without appreciable side shake in the neck 35 extending upwardly from the bottom of the casing 36 which is removably mounted on the underside of the housing 28. The cup 34 is yieldingly supported by a spring 37 the lower end of which rests on a screw plug 38 in the lower end of said neck. This plug can be screwed in or out to regulate the tension of the spring, and can be locked in adjusted position by a jam-nut 39. The steam inlet and outlet to and from the housing 28, and the nozzle for directing the steam upon the blades of the turbine rotor are not shown, as these parts may be of any suitable construction and are well understood.

The casing 36 is designed to be filled with high flash-point lubricating oil, insuring adequate lubrication of the lower portion of the shaft, where it is most needed.

Below the bottom of housing 28 the shaft runs in a long bearing 40, mounted in a tubular neck 41 supported between the bottom of the housing and the upper edge of the casing 36. Above the rotor 30 the shaft has a bearing 42 seated in flanged ring 43 resting in the central opening 44 in the top of the housing.

It is to be understood that the invention is not limited to the specific construction herein illustrated and described but can be embodied in other forms without departure from its spirit.

I claim—

1. In an apparatus for the purpose described, in combination, a head adapted to rotate on a vertical axis and provided with a plurality of outwardly extending tortuous non-widening passages to which liquids to be mixed or emulsified can be driven by centrifugal force, means for delivering the liquids to said passages at their inner ends, and means for rotating said head.

2. In an apparatus for the purpose described, in combination, a hollow carrier adapted to rotate on a vertical axis and having a plurality of delivery openings in its wall, a pair of disks mounted on said carrier to rotate therewith and providing between them a plurality of outwardly extending tortuous non-widening passages communicating at their inner ends with the openings in said carrier, means for delivering liquids into said carrier, and means for rotating the carrier.

3. In an apparatus for the purpose described, in combination, a plurality of pairs of disks arranged co-axially and adapted to

rotate on a vertical axis, each pair of disks providing between them a plurality of outwardly extending tortuous non-widening passages, means for delivering liquids to the inner ends of such passages, and means for rotating the disks.

4. In an apparatus for the purpose described, in combination, a horizontal disk having a plurality of outwardly extending 10 corrugated or saw-toothed surfaces on its upper side, a similar disk inverted upon the other, the corrugated or saw-toothed surfaces of the two providing a plurality of outwardly extending tortuous non-widening 15 passages, means for rotating the disks on a vertical axis, and means for delivering liquids to the inner ends of the said tortuous passages.

5. In an apparatus for the purpose described, in combination, a hollow carrier adapted to rotate on a vertical axis and having a plurality of openings in its wall, a plurality of pairs of disks mounted on said carrier co-axially therewith and with each 25 other, the disks of each pair providing between them a plurality of outwardly extending tortuous non-widening passages communicating at their inner ends with the openings in the wall of the carrier, removable 30 means for holding the disks on the carrier, and means for rotating the carrier and the disks.

6. In an apparatus for the purpose described, in combination, a disk arranged 35 horizontally to rotate on a vertical axis and having in its upper surface a plurality of radial recesses, inserts fitted in said recesses and having their upper surfaces corrugated or saw-toothed in form, a similar disk inverted upon the other and having inserts of 40 like form co-operating with the inserts of the lower disk to form a plurality of corrugated or saw-tooth passages, means for delivering liquids to said passages at their inner ends, 45 and means for rotating the disks on a vertical axis.

7. In an apparatus for the purpose described, in combination, a rotating head having a plurality of outwardly extending tortuous non-widening passages through which 50 liquids to be mixed or emulsified can be

driven by centrifugal force, means for delivering liquids to said passages at their inner ends, means for rotating said head, a stationary collecting trough encircling said head below the same to receive mixed or emulsified liquids discharged from said passages at the outer ends thereof, and means below said trough to receive the mixed or emulsified liquids collected thereby. 65

8. In an apparatus for the purpose described, in combination, a hollow carrier having a plurality of openings in its wall and provided with an outwardly extending flange, a collar threaded on the carrier at the upper end thereof above the said flange, a plurality of pairs of disks mounted upon said carrier between the flange thereof and the said threaded collar, said disks providing a plurality of outwardly extending tortuous non-widening passages communicating at their inner ends with the said openings in the carrier, means for rotating the carrier on a vertical axis, a stationary housing enclosing the disks and carrier to receive and collect liquids discharged from said passages, and means for delivering liquids to be mixed or emulsified into said carrier. 70

9. In an apparatus for the purpose described, in combination, a mixing or emulsifying head adapted to rotate on a vertical axis and comprising a hollow carrier provided with openings in its wall, and a plurality of pairs of disks mounted upon said carrier, the disks of each pair providing 80 between them a plurality of outwardly extending emulsifying passages communicating at their inner ends with said openings in the carrier, a vertical shaft upon which said carrier is mounted for rotation thereby, a stationary trough encircling the carrier below said disks and having a discharge spout, a stationary housing enclosing the head and mounted on said trough, to receive liquids discharged from the head and deliver such 85 liquids to the trough, and means carried by said housing for delivering liquids into said carrier. 90

In testimony whereof I hereto affix my signature.

CHRISTIAN F. PAUL, JR.
